UNITED STATES PATENT OFFICE.

RAYMOND D. JOHNSON, OF NEW YORK, N. Y.

VALVE.

1,321,750.

Specification of Letters Patent. Patented Nov. 11, 1919.

Application filed June 16, 1916. Serial No. 104,061.

To all whom it may concern:

Be it known that I, RAYMOND D. JOHNSON, a citizen of the United States, residing at New York, in the county of New York and State of New York, have invented certain new and useful Improvements in Valves, of which the following is a specification.

My invention relates to certain improvements in valves of the type shown in my previous Patent No. 1,030,890, patented July 2, 1912, the valve herein shown being of the same general construction.

These improvements relate to means for providing an automatic closure of the valve when the velocity of flow attains any prescribed magnitude; to means for insuring a more near perfect guidance of the movable valve member; and to means for indicating on the outside of the casing, the position of the valve within the casing, the indicating means being arranged to, if desired, automatically operate the control valve.

The manner in which I provide for these and other improvements will fully appear in the accompanying specification and drawings, in which—

Figure 1 is a longitudinal section of one form of valve, with pipe connections shown diagrammatically;

Fig. 2 is a transverse section on plane 2—2 of Fig. 1.

Fig. 3 is a detail showing the means for connecting the indicator to the control valve for operating the same.

Referring to the drawings, 1 represents a fluid conduit, which will for illustration be assumed to serve for conveying water under pressure. 3 is an enlargement of the conduit constituting the valve chamber and having a gradually expanding portion 2. Mounted within this chamber, and spaced from the walls thereof, is a cylindrical chamber 4 having a closed conical nose 5. The cylinder 4 is rigidly held in central position by a series of radial ribs 6. Sliding within the cylinder 4 is a plunger 7, also having a conical nose 8, both the noses having such a configuration as to subdivide the fluid smoothly as it enters and leaves the valve. The nose 8 is provided with a closure surface properly shaped to coöperate with a

corresponding valve seat 31. The cylinder 4 and plunger 7 are, as shown in Fig. 1, so shaped as to form an annular chamber A 55 within the operating cylinder 4, in addition to the central chamber B.

By means of a suitable external control valve and piping, either pipe-line pressure or atmospheric pressure may be applied in 60 the chambers A and B. Admitting pipe-line pressure to A, and exhausting it from B, opens the valve; reversing the operation closes the valve.

These operations may be effected by a control valve which may be of any suitable type,—as shown in Fig. 1, it is of the piston type and consists of a cylinder 10 having therein a piston valve provided with a chamber C, for alternately connecting the 70 pipes 13 and 14 to the exhaust 15. Pressure fluid is admitted to opposite sides of the piston valve by pipe 12 connected to a region of high pressure in the main fluid conduit 1. Pipes 13 and 14 lead respectively to chambers A and B.

The piston rod 16 of the control valve piston is pivoted to a lever 17, having one end connected by link 18 to the operating lever 19. The other end of lever 17, is pivoted at 20 to a fixed support.

In order to indicate the position of the plunger, a rod 28 is connected directly to the nose 8 of the plunger 7, and extends through the wall of the casing 3. The 85 pointer on the end of the rod and a scale 29 enable the location of the plunger to be determined. As shown in Fig. 3, this indicator rod 28 may, however, be connected to the control valve by means of a floating lever 90 30 and link 20'. As shown in Fig. 2, the indicator rod 28 is located within a fork-shaped cavity in the inner edge of the rib 6', and is thus protected against injury or displacement by the flow of water, or substances carried by such flow, through the passage near the end of the valve.

Another feature of improvement is the extension of ribs 6, beyond the end of the cylinder 4 to the wall of the casing 3, the 100 inner edges of the ribs 6 forming guides which provide a sliding contact and support for the plunger, all the way to its seat 31 on the inner wall of the casing 3.

Still another feature of improvement is the provision of means for causing the valve to automatically close in case of excessive velocity of flow in the main conduit, as 5 when a break in the pipe line occurs beyond the valve.

As shown in Fig. 1, the chamber A, is connected by pipes 32, 33 and 34 with a region of lower pressure, the rate of flow 10 through these pipes being adjusted by valve 35 or other suitable means. The pipe 34 is preferably connected at the point shown in Fig. 1, just above the seat of the main valve.

A pipe 39 is connected through valves 38 15 and 40 with pipes 37 and 41, leading to high pressure regions in the conduit 1, 2. A pipe 36 connects the pipe 39 with the interior of chamber B.

The operation of the valve is as follows:—
20 As shown in Fig. 1, the valve, of the horizontal type, is in the full open position with the piston valve 11 of the control-valve, closing the ports from the pipes 13 and 14 into the cylinder 10. If now it is desired to 25 close or partially close the valve, the operating lever 19 is moved to the right thereby connecting the pipe 13 through the chamber C with the exhaust 15 and admitting pressure water through pipe 12 into the cylinder 10 and thence into pipe 14. Pressure 30 water is thus admitted to chamber B, and chamber A is allowed to exhaust. The pressure upon the left-hand end of the plunger 7 causes the valve to begin its closing movement. As soon as the valve has reached its 35 desired position, as indicated by the pointer on the end of rod 28, the operating lever 19 is moved to restore the piston valve 11 to its neutral position, thereby cutting off both 40 the supply of pressure water to chamber B and stopping the exhaust from chamber A.

In case it is desired to provide for automatic closure of the valve upon the occurrence of an excessive flow of water in the 45 conduit, the chamber B is put into communication with a region of high pressure by opening one or the other of the valves 38 or 40. The valve 35 is also opened to connect the chamber A with a region of low 50 pressure. Assuming that the chamber B is connected to the high pressure region through pipe 37, the valve 38 and the valve 35 are each so adjusted that under normal 55 conditions, with the valve open, the flow through pipe 36 and pipe 32 will be so small as not to effect any change of position in the plunger 7. It will be understood that in the position of the valve as shown in Fig. 1, both chambers A and B are full of water 60 and that there is a constant slight leakage from chamber B to chamber A, since the sliding surfaces of the plunger 7 and piston 4 are not packed. Under normal flow conditions, therefore, the flow of water past the pipe

35 would not be sufficient to drain the chamber A to such an extent as to cause a movement of the plunger 7. When, however, an excessive flow occurs, as in case of a break in the pipe line beyond the valve, an abnormal diminution of pressure occurs in 70 the region to which pipe 34 is connected and the chamber A is gradually drained of water, while at the same time pressure water continues to be supplied to chamber B through the pipe 36. The valve therefor 75 gradually and automatically closes, thereby shutting off the water in the conduit beyond the valve. As these valves are adapted for and actually used in conduits of large diameter, as large as twelve feet, the importance of this feature of automatic closing of the valve will be readily understood, 80 the flow of water in case of a break, being of such volume as to cause great damage unless promptly shut off.

As shown in Fig. 3 the control valve is directly connected to the indicator rod 28. By means of this construction the main valve may be held at any desired degree of opening indefinitely since the motion of 90 the plunger tends to operate the control valve in a direction contrary to the attempted motion of the plunger. Thus, if the operating valve be moved to the right, the system of levers will operate about the 95 temporarily fixed point 50, thereby causing the admission of pressure water into chamber B and the exhaust of water from the chamber A, and the plunger 7 will move to the right carrying with it the pivotal point 50, and in turn operating the lever system about the point 51. This movement will cause the piston valve 11 to be moved in the reverse direction until it has assumed its neutral position, whereupon both the 100 pressure supply and the exhaust will be cut off and the plunger 7 will remain stationary at the point corresponding to the position of the operating lever 19. It will be obvious that once the lever 19 has been set to any given position, any movement of the valve, 110 will at once be counteracted by a movement of the control valve in such direction as to restore the main valve to its original position.

I claim:—

1. In combination, a fluid conduit having a contracted portion constituting a region of relatively low fluid pressure, a valve seat adjacent said contracted portion, a valve structure comprising a fixed cylinder supported within and spaced from the walls of said conduit, a plunger sliding within said cylinder, the cylinder and plunger being shaped to form a closed pressure chamber therebetween, means for operating the valve structure at will and means for automatically closing the valve when the rate 125

of flow in the conduit exceeds a definite limit, said means comprising a fluid connection between the cylinder and a point of relatively high pressure and a fluid connection between the said pressure chamber and a point of relatively low pressure.

2. In combination, a fluid conduit having a contracted portion constituting a region of relatively low fluid pressure, a valve seat adjacent said contracted portion, a valve structure comprising a fixed cylinder supported within and spaced from the walls of said conduit, a plunger sliding within said cylinder, the cylinder and plunger being shaped to form a closed pressure chamber therebetween, means for operating the valve structure at will and means for automatically closing the valve when the rate of flow in the conduit exceeds a definite limit, said means comprising a fluid connection between the cylinder and a point of relatively high pressure, means for adjusting the fluid conducting capacity of said connection, a fluid connection between said pressure chamber and a point of relatively low pressure and means for adjusting the fluid conducting capacity of said last-mentioned connection.

3. In combination, a fluid conduit having a contracted portion constituting a region of relatively low fluid pressure, a valve seat adjacent said contracted portion, a valve structure comprising a fixed cylinder supported within and spaced from said casing, a plunger sliding within said cylinder, the cylinder and plunger being shaped to form a closed pressure chamber therebetween, means for admitting pressure fluid to and exhausting it from said pressure chamber and said cylinder, a fluid connection between the cylinder and a point of relatively high pressure and a fluid connection between said pressure chamber and a point of relatively low pressure.

4. In combination, a fluid conduit having a contracted portion constituting a region of relatively low fluid pressure, a valve seat adjacent said contracted portion, a valve structure comprising a fixed cylinder supported within and spaced from said casing, a plunger sliding within said cylinder, the cylinder and plunger being shaped to form a closed pressure chamber therebetween, a fluid connection between the cylinder and a point of relatively high pressure, a fluid connection between the said pressure chamber and a point of relatively low pressure, means for independently adjusting the fluid conducting capacity of said connections, and means for admitting pressure fluid to and exhausting it from said pressure chamber and said cylinder.

5. In combination, a fluid conduit having a contracted portion constituting a re-

gion of relatively low fluid pressure, a valve seat adjacent said contracted portion, a valve structure comprising a fixed cylinder supported within and spaced from the walls of said conduit, a plunger sliding within said cylinder, the cylinder and plunger being shaped to form a closed pressure chamber therebetween, means for admitting pressure fluid to and exhausting it from said pressure chamber and said cylinder at will, means for automatically regulating said means to hold the valve in any desired position and means for automatically closing the valve when a predetermined rate of flow in the conduit is exceeded, comprising a fluid connection between the cylinder and a point of relatively high pressure, a fluid connection between the said pressure chamber and a point of relatively low pressure and means for adjusting the fluid conducting capacity of both of said connections.

6. A valve structure comprising a casing having a valve seat on its inner wall, a fixed cylinder supported within and spaced from the wall of said casing by ribs extending from the wall of the casing and the wall of the cylinder, a plunger sliding within said cylinder and having a closure surface coöperating with said valve seat, one of said ribs having a forked end portion, and an indicator rod directly connected to said plunger and extending between the forks of said rib and through the wall of the casing.

7. In combination, a fluid conduit having a contracted portion constituting a region of relatively low fluid pressure, a valve seat adjacent said contracted portion, a valve structure comprising a fixed cylinder supported within and spaced from the walls of said conduit, a plunger sliding within said cylinder, the cylinder and plunger being shaped to form a central chamber and an annular chamber therebetween, but so as to define a constricted passage way for the fluid to pass through the annular chamber into the central chamber, a fluid connection between the central chamber and a point of relatively high pressure in the conduit, and a fluid connection between said annular chamber and a point of relatively low pressure.

8. In combination, a fluid conduit having a contracted portion constituting a region of relatively low fluid pressure, a valve seat adjacent said contracted portion, a valve structure comprising a fixed cylinder supported within and spaced from the walls of said conduit, a plunger sliding within said cylinder, the cylinder and plunger being shaped to form a central chamber and an annular chamber therebetween, but so that a leakage can take place through the annular chamber into said central chamber,

a fluid connection between the central chamber and a point of relatively high pressure in the conduit, and a fluid connection between said annular chamber and a point of 5 relatively low pressure.

9. In a valve of the type recited having a region of relatively low pressure and in combination therewith elements having central and annular chambers, said elements comprising 10 a movable plunger, connections by which the pressure in said chambers is nor-

mally equalized when the movable plunger element is retracted, and a connection from the annular chamber to the region of relatively low pressure to automatically close 15 the valve in response to further drop in pressure at said region such as is induced by abnormal increase in flow, substantially as described.

In testimony whereof I affix my signature. 20

RAYMOND D. JOHNSON.
